UNITED STATES PATENT OFFICE.

HARRY L. HUNT AND LINCOLN A. HUNT, OF BIGELOW, MISSOURI.

PITMAN BOXING.

Application filed March 20, 1926. Serial No. 96,265.

This invention relates to new and useful improvements in pitman rods, and particularly to the boxings by means of which they are connected to the wrist pins of the driving shafts.

One object of the invention is to provide a device of this character wherein the boxing is capable of being adjusted to compensate for wear.

Another object is to provide a device of this character wherein the pitman rod is capable of being adjusted to take up wear, and loose play, at the boxing end of the rod, and at the point of connection with the sickle bar.

Another object is to provide a device of this character which is simple in construction, capable of being applied to the pitman rods now in use, and which can be manufactured at a comparatively low cost.

Other objects and advantages will be apparent from the following description when taken in connection with the accompanying drawing.

In the drawing:

Figure 1 is an elevation of a pitman and boxing, made in accordance with the present invention.

Figure 2 is a vertical longitudinal central sectional view through the device.

Referring particularly to the accompanying drawing, 10 represents a portion of the pitman rod, which has the strap 11 secured on one end. The bight portion of this strap 35 is provided with an opening 12, through which is disposed one end of an oppositely threaded rod 13. Engaged on this rod 13, at opposite sides of the bight portion, are the adjusting and retaining nuts 14 and 15. The intermediate portion of this rod 13 is provided with a wrench engaging portion 16, by means of which the rod may be turned.

Embracing the wrist pin 17, are the sections 18 and 19, of the bearing, said sections 45 being properly confined within a yoke-shaped frame 20. A block 21, is slidably supported in the frame 20 and has a flat face, on one side which bears against the section 18, while its opposite face is concave for 50 engagement by the adjacent end of the rod 13. In the opposite sides of the frame 20 are formed openings 22, which receive the lugs 23, of the arms of a yoke 24 which is made up of the pair of angle members 24'. The 55 other arms of said angle members are disposed in overlapping relation transversely

with respect to the sides of the frame 20, and said overlapping arms are provided with alining openings 25 through which is disposed the adjacent end of the rod 13. 60 Adjusting and clamping nuts 26 and 27, are engaged on the rod, at opposite sides of the overlapping arms of the yoke 24.

On the upper side of the frame 20 is an oil cup 28, which feeds lubricant to the 65 wrist pin and the bearing sections 18 and 19.

When the wrist pin and bearing blocks 18 and 19 wear to such an extent that a loose motion is present, the nuts 14 and 26 are turned away from the bight portion of the 70 strap 11, and the arms of the angle members 24', respectively, whereby to permit the rod 13 being moved against the block 21. The pressure of the rod 13 against the block 21 forces the section 18 against the wrist pin, and upon turning the nut 26 up against the angle members the frame 20 will be drawn 75 down, whereby to pull the bearing section 19 against the other side of the wrist pin. The nut 27 is then turned up tightly against 80 the angle members 24', whereby to hold the bearing sections in proper embracing engagement with the wrist pin. The nuts 14 and 15 are then manipulated to firmly clamp 85 the strap bight therebetween, and draw the pitman rod up to the desired position.

What is claimed is:

1. The combination with a wrist pin and pitman rod, of a two part bearing, a yoke-shaped frame supporting the bearing in 90 wrist pin embracing position, a removable yoke in the open end of the frame, an adjusting rod connected to the removable yoke and said pitman rod and in movable relation to one of said bearing parts, and means 95 for moving the adjusting rod and frame relative to each other whereby to tighten said bearing and take up on the pitman rod.

2. The combination with a wrist pin and pitman rod, of a two part bearing, a yoke-shaped frame supporting the bearing in 100 wrist pin embracing position, a strap on the pitman rod having an opening, a block slidably supported in the frame, an apertured yoke supported in the arms of the frame, 105 and an adjusting rod engaged in the openings of the strap and yoke and bearing against said slidable block.

3. A wrist-pin bearing take-up including 110 a frame one end of which is open, bearing blocks supported in the frame for embracing engagement with a wrist pin, a plano-

- concave block slidable in the frame and having its flat face engaged with one of said bearing blocks, a yoke having its arms operatively connected with the open end of the frame, a threaded rod disposed through the bight of the yoke and bearing against the concave face of the slidable block, and nuts engaged on the rod at opposite sides of the said bight.
4. The combination with a wrist pin and pitman rod, of a two part bearing embracing the wrist pin, a yoke-shaped frame supporting the bearing, a strap on the pitman rod, a block slidably supported in the frame, an oppositely threaded rod having an end engaged through the strap and an end disposed through an end of said frame and engaged with the block, adjusting nuts on the rod for clamping engagement with the strap, adjusting nuts on the rod for clamping engagement with the said frame end, and said rod being operatively engaged with one part of said bearing.
5. The combination with a wrist pin and

pitman rod, of a two part bearing, a frame supporting the bearing and having openings in the sides thereof, angle members each having a lug on one of its arms, engaged in one of said openings and having its other arm arranged in transverse relation to a side of the frame, a strap carried by the pitman rod and having an opening in its bight portion, the transverse portions of the angle members being apertured, a block disposed in the frame and against one of the parts of the bearing, an oppositely threaded rod having an end disposed through the bight opening and an end disposed through the angle members and in contact with the said block, clamping nuts on one end of the rod for binding engagement with the strap, and nuts on the other end of the rod for binding engagement with the said angle members, and lubricating means carried by the frame.

In testimony whereof, we affix our signatures.

HARRY L. HUNT.
LINCOLN A. HUNT.
